UNITED STATES PATENT OFFICE.

OTTO P. SCHUSTER, OF NORTH IRWIN, PENNSYLVANIA, ASSIGNOR TO WESTINGHOUSE ELECTRIC & MANUFACTURING COMPANY, A CORPORATION OF PENNSYLVANIA.

CONTROL APPARATUS.

Application filed August 12, 1922. Serial No. 531,321.

To all whom it may concern:

Be it known that I, OTTO P. SCHUSTER, a citizen of the United States, and a resident of North Irwin, in the county of Westmoreland and State of Pennsylvania, have invented a new and useful Improvement in Control Apparatus, of which the following is a specification.

My invention relates to switch mechanisms and it has particular relation to switches of the contacter type, commonly employed in the control of electric motors and the like.

An object of my invention is to provide means for adjusting the relative positions of the switch contact members so as to insure proper alinement.

Another object of my invention is to provide means for compensating for a reduction in contact pressure resulting from contact wear.

I am aware of the fact that it is common practice to provide some means for adjusting switch contact members. However, the majority of such devices are not completely effective.

My invention provides for three independent adjustments whereby the contact members, when in normal engagement, are always in perfect alinement.

My invention will be described in connection with the accompanying drawing, in which

Figure 1 is a view, partially in elevation and partially in section, of a switch mechanism embodying my invention,

Fig. 2 is a view of a portion of the movable contact switch member shown in Fig. 1, and

Fig. 3 is a view of a portion of the stationary contact member illustrated in Fig. 1.

Referring particularly to Fig. 1, a stationary contact member 1 is secured to a holding member 2 having a serrated surface, by means of a bolt 2^a. A supporting member or bracket 3 is also provided with a corresponding serrated surface, the two serrated surfaces co-operating for purposes of adjustment, as subsequently explained. A movable contact member 4 is mounted upon an adjustable member 5 and a rocker member 6, both of the latter being provided with co-operating serrated surfaces and being held in engagement by means of bolt 7.

The rocker member 6 is provided with a

shaft 8, which is carried by a lever arm 9 that is pivotally mounted upon a bracket 11. The bracket 11 supports a contact spring 12 of a familiar character and is mounted upon, and suitably insulated from, a stationary supporting bar or shaft 13.

For convenience, I have illustrated a switch of the cam-operated type, although it is evident that the switch may be operated electromagnetically or otherwise. I have shown the outline of a cam suitable for engaging with a roller 14 that is mounted upon the lever 9, for actuating the movable contact member 4.

The switch contact members are illustrated in closed position. The dotted line position of the contact member 4 indicates the inoperative or open position of the switch. The stationary holding member 2 is slotted as shown in Fig. 3, for the purpose of receiving the bolt 2^a, and it is evident that any desirable adjustment of the contact member 1 may be made along the direction of the slotted portion of the holding member 2.

The rocker member 6, illustrated in Fig. 2, is similarly slotted, for the purpose of receiving the bolt 7, whereby the movable contact member 4 may be moved toward or away from the contact member 1, without altering the position of the lever 9. By shifting the position of the member 5 along the serrated surface of the member 6, the ultimate compression or length of the spring 12 may correspondingly vary, the member 6, of course, rotating about the shaft 8.

Lateral alinement or movement of contact member 4 is effected, in a plane perpendicular to the plane of the drawing, by shifting the bracket 11 along the insulated shaft 13, a clamping member 15 with bolts 16 and 17 being provided for this purpose.

The switch is illustrated in perfect alinement, but it will be evident, to those skilled in the art, that variations in manufacture ordinarily prevent such exact alinement. It is for this purpose that the adjustments described above have been provided. In the operation of a switch of this character, the tip of the moving contact member 4, during the closing movement of the switch, first engages the tip of the stationary contact member 1, by reason of the biasing action of the spring 12. These tips are represented at the extreme right hand portions

of the contact members, as illustrated. As the switch is actuated to its fully closed position, the contact member 4 rolls along the surface of the stationary member 1 until 5 the heels or lower left hand portions of the contact members are in alinement, as represented by the line 18.

In service, the natural wear of the contact members results in a loss of contact 10 pressure and a corresponding decrease in the current-carrying capacity of the switch. As the switch members wear, the rocker member 6, in the closing movement of the switch, has less of an angular movement 15 about the shaft 8 in a counter-clockwise direction, and consequently there is less compression upon the contact spring 12. Normal contact pressure is restored by moving the adjustable member 5 downward to the 20 extent of one or more teeth of the serrated surface, so that in the closed position of the switch, a straight line, as 18, is maintained along the heels of the contact members.

25 I have illustrated my invention in a particular form, viz, as applied to a switch of the well-known contactor type. I believe, however, that my invention will readily lend itself to other applications, and I, 30 therefore, do not wish to be restricted to devices solely of the character described.

I claim as my invention:

35 1. A switch comprising stationary and movable contact members, said members being independently adjustable to effect relative alinement, a spring for rotating the movable member, and means compensating for decrease in contact pressure resulting from wear.

40 2. A switch comprising stationary and movable contact members, said members being adjustably mounted on serrated sur-

faces to effect relative contact alinement, a spring for rotating the movable member, and means for maintaining normal contact 45 pressure.

3. A switch comprising a stationary member adjustable along a given line, a co-operating movable member, means for adjusting its movement in the direction of its normal operation, a spring for rotating the movable member, and means for adjusting the movable member in a plane perpendicular to that of its normal operation.

4. A switch comprising a slotted stationary contact member and a supporting bracket therefor, each having serrated surfaces for mutual engagement, of a movable contact member, for engaging with said stationary member, means for rotating said movable member, an insulated shaft for supporting the movable member and means for adjusting the relative positions of said contact members in planes perpendicular to one another.

5. A switch comprising a movable contact member having a serrated surface and a similarly surfaced rotatable supporting member, of an operating lever for mounting the supporting member, a bearing bracket 70 for said lever, an insulated shaft for supporting the bearing bracket, a stationary contact member and a supporting bracket therefor, each having co-operating serrated surfaces in mutual engagement, means for 75 adjusting said members from tooth to tooth along said serrated surfaces and means for maintaining said bearing bracket in alinement with said contact members.

In testimony whereof, I have hereunto so subscribed my name this 8th day of August, 1922.

OTTO P. SCHUSTER.
